CLAIM

The ornamental design for a multi-pocketed storage bag, as shown and described.

DESCRIPTION

FIG. 1 is a front elevational view of a multi-pocketed storage bag showing my new design;

FIG. 2 is a right side elevational view thereof, the left side being a mirror image;

FIG. 3 is a rear elevational view thereof;

FIG. 4 is a top plan view thereof; and

FIG. 5 is a perspective view thereof.

The cross-hatching is intended to represent conventional fabric and to cover the entire surface represented.

FIG. 1.

FIG. 2.

FIG. 3.

FIG. 4.

FIG. 5.
